GUARD RAIL CLAMP

Harrison R. Akers, Tyler, Tex.

Application April 20, 1950, Serial No. 156,961

2 Claims. (Cl. 238—21)

1

This invention relates to railway equipment and more particularly to clamps for guard rails.

This invention is an improvement in the guard rail clamp disclosed and claimed in my Patent No. 2,385,248 issued September 18, 1945.

It is desirable that clamps for rail guards be of simple construction for ease of manufacture and installation. Moreover, the clamps must hold the guard rail at a predetermined distance from the traffic rail but must be easily adjustable to allow the guard rail to be moved closer to the traffic rail as the ball of the guard rail becomes worn with use in order to obviate the replacement of the worn guard rail.

Accordingly it is an object of my invention to provide a new and improved clamp for guard rails.

It is another object of my invention to provide a new and improved clamp for guard rails which is of simple construction.

It is still another object of my invention to provide a new and improved adjustable clamp for guard rails.

Briefly stated, my new and improved guard rail clamp comprises a pair of tapered turn out filler blocks disposed between the guard rail and the traffic rail adjacent the ends of the guard rail. The filler blocks are adjustably secured relative to one another by a rod. The space between the guard rail and the traffic rail is determined by the distance between the filler blocks. The guard rail and the traffic rail are held against outward movement by a C-shaped yoke. A wedge shaped key cooperates with one end of the yoke to limit the outward movement of the guard rail while a take up block having an arcuately recessed end cooperates with the other arcuate end of the yoke to allow a limited movement between the guard rail and the traffic rail. In one application a pair of yokes are employed, one adjacent each end of the guard rail. The wedged shaped keys associated with yokes face in opposite directions and cooperate with the tapered turn out filler blocks which also face in opposite directions to wedge the guard rail against movement relative to the traffic rail. In another application, only one yoke and its associated key and take up block are employed. In this case a pair of adjustable cooperating wedge shaped spacer blocks are employed to prevent movement of the guard rail toward the traffic rail. The wedge shaped keys and the spacer blocks are selectively adjustable to allow the distance of the guard rail from the traffic rail to be varied as desired.

2

For a better understanding of my invention reference may be had to the following specification taken in connection with the accompanying drawings and its scope will be pointed out in the appended claims.

In the drawing,

Figure 1 is a perspective view of a section of traffic rail with the guard rail attached by means of the present invention;

Figure 2 is a top plan view of the device shown in Figure 1;

Figure 3 is a transverse section taken on line 3—3 of Figure 2;

Figure 4 is a transverse section taken on line 4—4 of Figure 2;

Figure 5 is a perspective view of a turn out filler block and a portion of the connecting rod;

Fig. 6 is a top plan view of a section of traffic rail attached by means of a single yoke and the spacer block;

Figure 7 is a transverse section taken along line 7—7 of Figure 6;

Figure 8 is a perspective view of a yoke, key and take up block; and,

Figure 9 is a perspective view of a pair of cooperating spacer blocks.

Referring now particularly to Figures 1 to 5 and 8 of the drawing, a guard rail 10 is shown attached to a traffic rail 11 by means of the guard rail clamp of my invention. The guard rail clamp comprises a pair of C-shaped yokes 12 and 13. Each of the yokes 12 and 13 has a body 14 which lies beneath and spans the rails 10 and 11 and whose inwardly turned ends 15 and 16 confront the outer surfaces of the webs 17 and 18 of rails 10 and 11, respectively. The ends 16 of yokes 12 and 13 are cut obliquely and bear against correspondingly oblique surfaces 19 of wedge keys 20 and 21, respectively interposed between ends 16 of yokes 12 and 13, respectively, and the web 18 of guard rail 11.

The end 15 of yokes 12 and 13 are of arcuate shape and lie in correspondingly shaped arcuate sockets or recesses 22 in take up blocks 23 and 24, respectively. The take up blocks 23 and 24 are interposed between the ends 15 of yokes 12 and 13 and the outer surface of web 17 of the guard rail 10.

The turn out filler blocks 25 and 26 each consist of a body 27 shaped to conform to the space between the webs 17 and 18 of guard rail 10 and traffic rail 11 at the turn out 29 or 30 of guard rail 10. Each of the filler blocks 25 and 26 is provided with a lower transverse flange 31 beneath the outer or wide end provided with an

aperture to receive the rod 32. The opposite or narrow ends of the filler blocks 25 and 26 are slotted at 33 to accommodate a bolt 34 or 35 which extend from web 17 to web 18 of rails 10 and 11.

Returning to the yokes 12 and 13 and their associated components, it will be observed that each of the wedge keys 20 and 21 is provided with a lower flange 36 which is disposed in the slot or channel 37 between end 16 and main body 14 of its associated yoke 12 or 13. Flange 36 projects outwardly beyond the oblique surface 19 of the wedge key 20 or 21 and is provided with a plurality of apertures 38 each of which is adapted to receive a cotter key 39. The cotter keys 39 prevent movement of the wedge keys 20 and 21 toward each other since they abut the ends 16 of yokes 12 and 13. Movement of wedge keys 20 and 21 away from each other is prevented by the oblique ends 16 and the correspondingly oblique surfaces 19 of the wedge keys 20 and 21. It will be noted that the ends 16 of yokes 12 and 13 are inclined toward the turn outs 29 and 30 respectively. Each of the take up blocks 23 and 24 is also provided with a flange 40 which is disposed in a slot 41 provided between the arcuate end 15 and the body 14 of the yokes 12 and 13.

In operation, the guard rail 10 is arranged in parallel relation with the traffic rail 11 and the yokes 12 and 13 are passed transversely under the rails 10 and 11 adjacent the turn outs 29 and 30. The ends 15 and 16 of each yoke 12 and 13 face the outer surface of webs 17 and 18, respectively. The take up blocks 23 and 24 are then set in position with the arcuate ends 15 of yokes 12 and 13 resting in the recesses 22 of blocks 23 and 24, respectively. If the guard rail 10 is new, the cotter keys 39 are inserted in the apertures 38 of flanges 36 of wedge keys 20 and 21 which are nearest the traffic rail 10. Ends 15 of yokes 12 and 13 will then abut the cotter key 39. It will be noted that the wedge keys 20 and 21 are each provided with a recess or slot 42, Figure 8, which permits the keys 20 and 21 to be positioned adjacent the ends of bolts 34 and 35 in order to permit yokes 12 and 13 to be positioned as close as possible to turn outs 29 and 30.

The turn out filler blocks 25 and 26 are then placed between traffic rail 11 and turn outs 29 and 30, respectively, and the connecting rod 32 is passed through the apertures in the flange 31 of the blocks 25 and 26. When filler blocks 25 and 26 are in proper position between the rails 10 and 11, the nuts 43 and 44 on the threaded ends of rod 32 are tightened against the lock washers 45 abutting filler blocks 25 and 26, respectively.

The wedging action of filler blocks 25 and 26 between traffic rail 11 and turn outs 29 and 30 and the wedging action of keys 20 and 21 between the traffic rail 11 and ends 15 of yokes 12 and 13 will automatically tighten all parts as filler blocks 25 and 26 move toward each other. Guard rail 10 will therefore be held rigidly to traffic rail 11.

Should it become necessary to move guard rail 10 closer to traffic rail 11 to compensate for wear on the ball 49 of guard rail 10, the nuts 43 and 44 are loosened as well as the nuts on bolts 34 and 35. The cotter keys 39 are moved into the next apertures 38 and the ends 16 are therefore moved farther away from traffic rail 11. This causes guard rail 10 to be moved closer to traffic rail 11. The nuts 43 and 44 are then tightened again. It will be noted that filler blocks 25 and 26 will now be farther from each other than

formerly. As the ball 49 of guard rail 10 continues to wear, the above operation is repeated until the wedge keys 20 and 21 are in the position illustrated in Figure 2. If the ball 49 continues to wear, no further adjustment can be made and a new guard rail 10 will have to be provided.

One of the advantages of the guard rail clamp of my invention lies in the ease of installation and adjustment of guard rail 10. One man can install or adjust the guard rail 10. Moreover, no permanent parts, such as the spikes 10', need be removed to effect the adjustment of the guard rail 10. If desired, a third yoke 47 and an associated wedge key 48 and take up block 49, shown in broken lines in Figure 2, may be installed between yokes 12 and 13 to help hold guard rail 10 and traffic rail 11 in rigid relation to each other.

Figures 6, 7 and 9 illustrate a modified form of the above described apparatus in which only yoke 50 and its associated wedge key 51 and take up block 52 are employed with turn-out filler blocks 25 and 26. Yoke 50, key 51 and blocks 52 are identical in construction with yokes 12 and 13, keys 20 and 21, and blocks 23 and 24 and will therefore not be described in detail. Yoke 50 is disposed intermediate filler blocks 25 and 26 and cooperates with a pair of spacer blocks 53 and 54 to hold guard rail 10.

Spacer block 53 has a side 55 adapted to abut the web 17 of guard rail 10 and an opposite oblique side provided with groove 56. The co-operating spacer block 54 is provided with a tongue 57 which fits in the groove 56, the oblique side of block 53 contacting a corresponding oblique side of block 54. The tongue 57 is provided with a plurality of holes 58 each of which is adapted to receive a cotter key 59. As is shown in Figure 6, the cotter key 59 abuts the large end 40 of blocks 53 preventing movement of blocks 53 relative to block 54. Blocks 53 are also provided with an aperture 60 which receives the rod 32 which connects turn out filler blocks 25 and 26.

The yoke 50, key 51 and blocks 52 operate in the same manner as described above and enable the guard rail 10 to be adjusted relative to traffic rail 11. Spacer blocks 53 and 54 are movable relative to each other and are also adjustable due to the provision of apertures 58 and cotter key 59. Spacer blocks 53 and 54 help to maintain rails 10 and 11 properly spaced by preventing rail 10 from approaching too closely to rail 11.

The arrangement shown in Figure 6 allows for a limited range of movement of traffic rail 11 with respect to rail 10. The arcuate end 15 of yoke 50 allows a limited pivotal movement of block 52 about end 15 in order to allow traffic rail to creep or move as it expands and contracts with change in temperature.

While there has been shown and described preferred embodiments of my invention it will be apparent to those skilled in the art that changes and modifications can be made without departing from my invention and it is the aim in the appended claims to cover all such changes and modifications as fall within the true spirit and scope of my invention.

What is claimed is:

1. In combination: a traffic rail; a guard rail 70 having an intermediate portion extending parallel to said traffic rail and turned out end portions extending away from said traffic rail; a pair of C-yokes; one of said yokes being positioned adjacent one of said turned out end portions and the other of said yokes being positioned

adjacent the other of said turned out end portions, each of said yokes transversely underlying said traffic rail and said intermediate portion and having inwardly turned ends confronting the outer web surface of said rails, one of said ends being inclined with respect to the adjacent rail web and the other end arcuated; a wedge key for each of said yokes, each of said wedge keys having an inclined side abutting the inclined end of its associated yoke and having a flange provided with a plurality of spaced apertures; means disposed in one of said apertures for limiting movement of each of said wedge keys relative to its associated yoke, each of said wedge keys cooperating with the inclined yoke end of its associated yoke to effect perpendicular displacement of its associated yoke with respect to said traffic rail; a take-up block for each of said yokes, each of said take-up blocks being interposed between the arcuated end of its associated yoke and the adjacent rail web; a pair of spaced turn out blocks having wedging engagement between confronting sides of said end portions and said traffic rail; and a rod extending uninterruptedly through each of said turn out blocks for connecting said turn out blocks against movement relative to one another.

2. In combination; a traffic rail; a guard rail having an intermediate portion extending parallel to said traffic rail and turned-out end portions extending away from said traffic rail; a C-yoke

transversely underlying said rails and having inwardly turned ends confronting the outer web surfaces of said rails, one of said ends being inclined with respect to the adjacent rail web and the other end arcuated; a wedge key having an inclined side abutting said inclined end; a flange extending from said key adjacent said side and provided with a plurality of vertical apertures; means for limiting movement of said key with respect to said inclined end disposed in one of said apertures; a take-up block interposed between the arcuated end and the adjacent rail web; a pair of spaced turn-out blocks having wedging engagement between confronting sides of said end portions and said traffic rail; a rod extending from one to the other of said turn out blocks and through openings in the outer ends of the latter, and means threaded on each end of said rod for preventing movement of said blocks relative to one another.

HARRISON R. AKERS.
